PIMENTO ROASTER

Mont M. Linkenauger, Sumter, S. C.

Application January 18, 1936, Serial No. 59,781

1 Claim. (Cl. 146—46)

This invention relates to the roasting of pimientos and other vegetables and fruits whereby the skins may be readily removed, and has for its primary object to provide an inexpensive mechanism of simple construction for properly presenting the material to the flames.

Another object of the invention consists in providing a mechanism which is highly efficient in operation and which can be operated at a minimum cost.

A further object of the invention resides in a method of advancing the pimientos or the like through the flame and rotating them so that a uniform application of the flame to the entire surface of each article is insured.

Other objects and advantages of the invention will be apparent from the following description when taken in connection with the accompanying drawing, in which,

20 Figure 1 is a side elevational view of the complete device.

Figure 2 is a vertical sectional view taken on line 2—2 of Figure 1, and

25 Figure 3 is a fragmentary sectional view taken on line 3—3 of Figure 1.

Referring to the drawing in more detail, the numeral 1 indicates any suitable frame construction provided with standards 2 of graduated height so as to support the track 3 for the oven 30 at the desired inclination.

The track 3 comprises two angle irons 4—4 fixed to the upper ends of the standards 2 with their outer flanges extending vertically and their inner flanges directed toward each other. The 35 vertical flanges serve as guards to direct the movements of the oven as will later appear and the inwardly directed flanges form supports for bearings 5 in which are mounted transversely extending rollers 6. Four of these rollers are indicated in the present embodiment of the invention but it will be obvious that the number may be increased or diminished as circumstances warrant. It will be noted that the diameters of the rollers are such that their peripheries are 45 somewhat below the upper edges of the vertical webs of the angle irons 4 thereby permitting the oven, to be described, to be disposed slightly below the upper edges of the webs.

The oven or roasting chamber comprises a 50 channel iron 7 of the desired length and width and a semi-circular hood 8 of the same length and substantially the same width. The member 8 is inverted as indicated in the drawing, and its legs are preferably riveted to the vertical webs 55 of the respective angle irons 4. Adjacent its

upper end, which is the end at which the articles to be treated are received, the roasting chamber is provided with a smoke stack 9 and a baffle plate 10 to direct the products of combustion to the entrance to the stack. Adjacent the lower and exit end of the chamber 8 a burner 11 is mounted at such angle as to direct its flame up the length of the oven. A valve 12 is of course provided for the purpose of regulating the intensity of the flame as may be desired.

10 Fixed to the underside of the oven 8 and disposed between it and the lateral webs of the angle irons 4 is a bar 13. To this bar is pivotally connected a rod 14 which has its opposite end fixed to an eccentric strap 15. This strap cooperates 15 with an eccentric 16 on a shaft 17 which is mounted in bearings 18 adjacent the entrance to the oven 8. Rotary motion is imparted to shaft 17 by means of a belt 19 cooperating with a wheel 20 fixed to one end of shaft 17 and a drive wheel 21 fixed to a shaft 22. The shaft 22 may be driven 20 by any desired means (not shown).

Operation of the eccentric strap 15 and connecting rod 14 will of course cause the oven 8 to be reciprocated over the roller bearings and in order to avoid undue jarring action springs 23 are provided. These springs are connected to the sliding bar 13 and to a fixed bar 24 disposed slightly beyond the lower limit of movement of bar 13. It will be apparent therefore that the springs 23 act as a shock absorber to eliminate excessive jarring of the parts.

25 The pimientos or other articles to be treated are fed to the upper end of the oven by a conveyer 25 or other suitable means cooperating with a bridge member 26, and the treated articles are 30 discharged from the lower end of the oven onto a conveyer 27 or other suitable means for conveying them to the next point of operations.

35 In the operation of the device, the burner 11 is ignited and the valve 12 adjusted to provide the desired intensity of flame. The drive pulley 21 is now set in operation so as to impart the necessary reciprocatory motion to the oven 8, and the articles are fed into the open upper end of the oven by means of the conveyer 25. The inclination of the oven is such that there is a definite tendency for the articles to move by gravity down the length of the oven and this tendency is augmented by the reciprocations of the oven 50 which overcomes the inertia of the articles and causes them to rotate about their axes as they travel toward the conveyer 27. The downward travel of the oven of course slows down the speed 55 of rotation of the articles momentarily. It will

thus be apparent that the surfaces of the articles are repeatedly presented to the flame in a very thorough and efficient manner thus avoiding any possibility of untreated articles being discharged from the oven.

5 From the foregoing description and the accompanying drawing it will be apparent that I have devised an exceedingly simple and inexpensive method and apparatus for the treatment of pimientos and like articles in bulk; that individual treatment of the several articles is provided for without separate handling as is required in many prior devices; and that the cost of operation is reduced to a minimum.

10 15 In accordance with the patent statutes I have described what I now believe to be the preferred construction of the apparatus, but inasmuch as various minor changes may be made in the details of construction without departing from the spirit of the invention it is intended that all such

changes be included within the scope of the appended claim.

What I claim is:

A roasting mechanism for pimientos and the like comprising a base member including inclined angle bars and a cross-bar at the top of the base, an elongated, open-ended oven reciprocably mounted on the base, a plurality of rollers interposed between the oven and base, the bottom of the oven being flat and extending downwardly 10 in a single plane from end to end of the oven, a burner at the lower end of the oven and adapted to direct its flame toward the opposite end of the oven, means for reciprocating the oven, a cross-bar on the bottom of the oven to which the reciprocating means is attached, and a spring having its respective ends connected to the cross-bar on the oven and the cross-bar on the base.

MONT M. LINKENAUGER. 20
